Primary Examiner — Khawaja Anwar*(74) Attorney, Agent, or Firm* — Knobbe Martens Olson & Bear, LLP(57) **CLAIM**

The ornamental design for a pump, as shown and described.

DESCRIPTION

FIG. 1 is a front, left, and top perspective view of a pump; FIG. 2 is a back, right, and bottom perspective view of the pump of FIG. 1; FIG. 3 is a front elevational view of the pump of FIG. 1; FIG. 4 is a back elevational view of the pump of FIG. 1; FIG. 5 is a top plan view of the pump of FIG. 1; FIG. 6 is a bottom plan view of the pump of FIG. 1; FIG. 7 is a right elevational view of the pump of FIG. 1; and, FIG. 8 is a left elevational view of the pump of FIG. 1. The broken lines shown in drawings show portions of the pump and form no parts of the claimed design.

 U.S. Appl. No. 14/013,448, filed Aug. 29, 2013, Woven Vascular Device End Treatments.
 U.S. Appl. No. 14/013,588, filed Aug. 29, 2013, Woven Radiopaque Patterns, U.S. Pat. No. 8,852,227, Oct. 7, 2014.
 U.S. Appl. No. 14/013,530, filed Aug. 29, 2013, Offset Vascular Treatment Devices, U.S. Pat. No. 8,715,316, May 6, 2014.
 U.S. Appl. No. 14/132,493, filed Dec. 18, 2013, Variably-Shaped Vascular Devices, U.S. Pat. No. 8,721,677, May 13, 2014.
 U.S. Appl. No. 14/093,796, filed Dec. 2, 2013, Flow Diverting Devices, U.S. Pat. No. 8,715,317, May 6, 2014.
 U.S. Appl. No. 14/093,831, filed Dec. 2, 2013, Flow Disrupting Devices, U.S. Pat. No. 8,728,117, May 20, 2014.
 U.S. Appl. No. 14/093,810, filed Dec. 2, 2013, Methods of Decoupling Joints, U.S. Pat. No. 8,870,910, Oct. 28, 2014.
 U.S. Appl. No. 14/254,271, filed Apr. 16, 2014, Methods of Aspirating Thrombi, U.S. Pat. No. 8,932,320, Jan. 13, 2015.
 U.S. Appl. No. 14/260,655, filed Apr. 24, 2014, Aspiration Systems, U.S. Pat. No. 8,832,321, Jan. 13, 2015.
 U.S. Appl. No. 14/167,118, filed Jan. 29, 2014, Variable Porosity Flow Diverting Devices, U.S. Pat. No. 8,845,679, Sep. 30, 2014.
 U.S. Appl. No. 14/167,138, filed Jan. 29, 2014, Methods of Manufacturing Flow Diverting Devices, U.S. Pat. No. 8,863,631, Oct. 21, 2014.
 U.S. Appl. No. 14/258,424, filed Apr. 22, 2014, Non-Cylindrical Mandrels, U.S. Pat. No. 8,910,555, Dec. 16, 2014.
 U.S. Appl. No. 14/224,605, filed Mar. 25, 2014, Balloon Catheters, U.S. Pat. No. 8,828,045, Sep. 9, 2014.
 U.S. Appl. No. 14/224,599, filed Mar. 25, 2014, Methods for Modifying Hypotubes, U.S. Pat. No. 8,813,247, Aug. 26, 2014.
 U.S. Appl. No. 14/224,551, filed Mar. 25, 2014, Methods for Slag Removal, U.S. Pat. No. 8,859,934, Oct. 14, 2014.
 U.S. Appl. No. 14/224,637, filed Mar. 25, 2014, Variably Heat-Treated Tubular Devices.
